UNITED STATES PATENT OFFICE.

SETH A. BROWN, OF BUFFALO, NEW YORK, ASSIGNOR TO THE BUFFALO DENTAL MANUFACTURING COMPANY, OF SAME PLACE.

VULCANIZER.

SPECIFICATION forming part of Letters Patent No. 630,650, dated August 8, 1899.

Application filed February 19, 1897. Serial No. 624,259. (No model.)

To all whom it may concern:

Be it known that I, SETH A. BROWN, residing in the city of Buffalo, in the county of Erie and State of New York, have invented certain 5 new and useful Improvements in Vulcanizers for Dental and other Purposes, of which the following is a specification.

My invention relates to certain improvements, as hereinafter claimed, by which the 10 apparatus may be cheaply and durably constructed, be easy of operation, and not liable to get out of order.

In the accompanying drawings, showing the construction of the apparatus with some 15 modifications thereof, Figure 1 is an outside view or elevation; Fig. 2, a view, partly in section, taken through the dotted line $\alpha\alpha$, Fig. 3, showing section of pot and cover, frame, and supporting-lugs and part section 20 of clamp-bar, means of journaling the clamp to the frame, and the screw to fasten the cover on the pot. Fig. 3 is an elevation at right angles to Fig. 1, showing by dotted lines the clamp swung downward; Fig. 4, a general 25 top view; Fig. 5, a top view of base or frame, showing guides and supporting-lugs; Fig. 6, a top view of modified form of base or frame; Fig. 7, a sectional view of base or frame; Fig. 8, a sectional view of modified form of base or 30 frame, showing supporting-ring and guides; Fig. 9, another modification showing base or frame in section, with supporting-ring partly in section; Fig. 10, a top view of supporting-ring; Fig. 11, a side view of supporting-ring at 35 right angles to view in Fig. 9; Fig. 12, a sectional view of modified form of clamp-joint or bearing with the frame. Fig. 13 shows a portion of the top of clamp-bar, partly in section and the cover in section, with ball-bearing 40 ing, all enlarged; Sheet 2, Fig. 14, general view, enlarged, showing modified form of ball-bearing clamp. Fig. 15 shows leg 2 of ball-bearing clamp; Fig. 16, a leg or bolt of clamp; Fig. 17, a top view of clamp.

45 My invention differs principally from previous devices in that the pressure of the clamp or clamping device is brought to bear upon the bottom of the pot instead of upon a collar brazed upon the pot at its top. A ball-bearing for the clamp-screw is also a novel 50 feature of construction.

The base or frame A is preferably cast of common or of malleable iron, and has three or more internal ribs $b b b^2$ (in the drawings four are shown) to act as guides to retain the 55 pot B in the center thereof. At or near the bottom of said ribs are lugs b^3 , preferably cast integrally therewith, for the purpose of supporting the bottom of the pot B, thus leaving a space between the pot and frame or jacket 60 for the heat to rise and pass over the surface of the former. One of said ribs b^2 , as shown in Figs. 7 and 8, can be separate from the frame A at or near the lugs b^3 or the ring J, (in the modification,) but movably attached 65 to the frame by means of rivets long enough to permit it to have a slight motion horizontally. The frame can be tapped at or near the middle of this detached rib b^2 and a thumb-screw *i* inserted therein. The latter is adapted 70 to bear against the rib and force it away from the frame A and against the pot B for the purpose of temporarily securing the latter in the frame A while the cover C is being pried off. Two holes are bored in opposite sides of 75 the frame A to receive the pins or journals *a* of the clamp D.

The pot B can be made in any suitable way; but it is preferably stamped or drawn out of a solid piece. It can have a ring brazed on 80 its upper end, if desired, to form a wide face for the packing-joint, or, as in the present case, be left straight and uniform throughout, thus retaining the original strength and temper, which would otherwise be lost by brazing. 85 A gas-burner or other suitable heater can be placed under it in the frame A.

The cover C can be tapped to receive a suitable steam-gage, thermometer, safety-valve, blow-off, and gas-regulator, as in the usual 90 preferred form of construction. It can be slightly countersunk to receive the end of the binding-screw E, or, as shown in Fig. 13, have a ball-race in it stop for antifriction-balls *c*, which are held in place by a suitable ring *e*. 95 It has the usual annular groove in its lower side for holding the steam-packing and to receive the end of the pot B.

The clamp D has a screw E, handle F, and legs *d d*, which latter can be sprung slightly 100 to permit the pins *a a* to enter the holes or bearings in the frame A. It will be seen that

the clamp can be swung downward and out of the way. When in position over the cover C, the screw E can be turned by a suitable wrench, thus closing the joint between the cover and the pot. Said screw can bear directly upon the cover, as shown in Fig. 2; but I prefer to have it bear upon the balls c, as shown in Fig. 13, because this method reduces the friction which would otherwise exist between the cover and the screw.

The ball-bearing for the clamp-screw is not limited to the particular form of clamp shown, but may be applied to a great variety of cross-bar vulcanizers.

- 15 In a modified form instead of the screw E bearing upon the balls in the cover a nut and bolt clamping device may be used having balls interposed between the nut and clamp-bar. One such device is shown on Sheet 20 2 of the drawings in Figs. 14, 15, 16, and 17, in which the clamp-bar 1 has a slight projection on its lower side adapted to bear on the cover C, has a leg 2 hinged at one end by a pin 6, so as to be movable in a plane parallel to 25 its length, and has a bolt-hole with a ball-race encircling it, in which antifriction-balls are placed. It can have a handle F attached. The leg 2 is forked at its top to receive the bar 1 and is hinged to the frame A by a screw 8 30 passing through its lower end, or in any suitable manner, so as to permit it to swing in a plane at right angles to the length of the bar 1. The threaded leg or bolt 3 is hinged to the opposite side of the frame A by the screw 8 35 and is adapted to pass through the bolt-hole in the bar 1. A conical-faced nut 4 (shown in section) is screwed onto the bolt 3 and is adapted to bear against the balls c c, thus forcing the bar 1 downward onto the cover C. This form of clamp is very powerful on 40 account of the leverage, the pin 6 acting as a fulcrum. The entire clamp can be swung downward out of the way. It will thus be seen that in consequence of the pressure or 45 strain coming on the entire length of the pot and on the bottom thereof greater resistance is offered than if the strain were placed upon a narrow collar, as in the usual form.

Among various other modifications which 50 may be mentioned are those shown by Figs. 6 and 8. Instead of pot B being supported by the lugs b³ it is supported by a ring J, formed near the lower part of the ribs b and smaller than the inside of the base or frame, so as to 55 allow a space for the heat to rise. As shown by Fig. 8, the loose guide b² can be actuated by means of a cam-lever K instead of the thumb-screw i, Fig. 7.

As shown by Figs. 9, 10, and 11, the pot B, 60 instead of resting on the ring J or lugs b³, rests in a separate ring G, having an internal flange g, and the pins a a of the clamp D enter the holes o o. The standard or base H has lugs h h for supporting the ring G and its contents and 65 has a jacket I, preferably of sheet metal, fitted to its upper part for the purpose of retaining the heat. By this arrangement the pot B, cover

C, and clamp D can be lifted out together when desired.

As shown in Fig. 12, instead of the bearings 70 or pins a a being in one piece with the legs d d, the latter are bored transversely at their lower ends and receive a screw n, which enters the frame A. The frame A or ring G can be elements of various sorts of clamping devices, as may hereinafter suggest themselves. I therefore do not limit myself to the particular form of clamp shown.

In the clamping device used to retain the pot in the frame I do not limit myself to the 80 rib and clamp shown, but the ribs can all be cast integrally with the frame, the screw or cam be put in any suitable place, and a separate movable shield be used in a similar manner and for the same purpose as the detached rib b², or the cam or screw can bear directly against the pot; but I prefer a shield between to prevent wear and damage.

I claim—

1. The combination of a pot or boiler, a 90 cover for the same, a base or frame for supporting the bottom of the pot or boiler and a suitable clamp attached to said base or frame and adapted to secure the cover on the pot.

2. The combination of a pot or boiler, a 95 cover for the same, a hollow base or frame for supporting the bottom of the pot, ribs or guides on the inside of said base or frame for retaining the pot in the center thereof and a clamp attached to the base or frame and adapted to hold the cover on the pot.

3. The combination of a pot or boiler, a cover for the same, a hollow base or frame having internal lugs for supporting the bottom of the pot, and a clamp attached to the 105 base or frame to hold the cover on the pot.

4. The combination of a pot or boiler having its periphery or shell of an approximately uniform thickness, a cover for the same, a base or frame for supporting the bottom of the 110 pot, and a clamp attached to said base or frame for holding the cover on the pot.

5. The combination of a pot or boiler, a cover for the same, a hollow base or frame for supporting the bottom of the pot, means for 115 securing the pot therein and a clamp attached to said frame and adapted to secure the cover on the pot.

6. The combination of a pot or boiler, a cover for same, a hollow base or frame adapted 120 to support the bottom of the pot, a loose rib or piece in the interior of the base or frame adapted to be forced against the pot, and a clamp attached to the base for holding the cover on the pot.

7. The combination of a pot or boiler, a cover for the same, a hollow base or frame for supporting the bottom of the pot, and containing a loose rib or piece, a screw inserted in the periphery of the frame and adapted to 130 bear against said rib or piece and a clamp attached to the frame for the purpose set forth.

8. In a vulcanizer a hollow base or frame, a pot and cover adapted to be supported there-

in, and a clamp hinged to opposite sides of said frame and adapted to swing in a vertical plane, for the purpose specified.

9. In a vulcanizer the combination of a pot or boiler, a cover for the same, a base or frame for holding the pot, a ball-bearing screw-clamp connected with said frame and adapted to hold the cover on the pot.

10. In a vulcanizer the combination of a pot or boiler, a cover for the same, a frame or

base for supporting said pot, a screw-clamp connected with said frame or base, and balls interposed between the cover and the binding-screw of said clamp for the purpose set forth.

SETH A. BROWN.
